Primary Examiner — George D. Kirschbaum

(57) **CLAIM**

We claim the ornamental design for a particle characterization device, as shown and described.

DESCRIPTION

1. Particle characterization device

1.1 is a bottom view.

1.2 is a rear view.

1.3 is a front view.

1.4 is a side view.

1.5 is a front perspective view.

1.6 is a side view of the opposite side of 1.4.

1.7 is a top view.

The broken lines shown in the drawings illustrate portions that form no part of the claimed design.

The dash-dot lines shown in the drawings represent the bounds of the claimed design.
